UNITED STATES PATENT OFFICE.

WILLIAM BURROWS MINOR, OF DEPOSIT, NEW YORK.

ACETYLENE-GAS GENERATOR.

SPECIFICATION forming part of Letters Patent No. 651,196, dated June 5, 1900.

Application filed June 29, 1899. Serial No. 722,256. (No model.)

To all whom it may concern:

Be it known that I, WILLIAM BURROWS MINOR, of Deposit, in the county of Broome and State of New York, have invented a new and Improved Acetylene-Gas Generator, of which the following is a full, clear, and exact description.

The object of the invention is to provide a new and improved acetylene-gas generator which is simple and durable in construction, very effective and automatic in operation, and arranged to prevent waste of carbid or gas and generate gas in amounts only as required and with a uniform pressure at the burners, the arrangement permitting a ready recharging with carbid without danger of gas escaping into a room or without interruption of the generation of gas.

The invention consists of novel features and parts and combinations of the same, as will be fully described hereinafter and then pointed out in the claims.

A practical embodiment of my invention is represented in the accompanying drawings, forming a part of this specification, in which similar characters of reference indicate corresponding parts in all the views.

Figure 1 is a sectional side elevation of the improvement. Fig. 2 is an enlarged transverse section of one of the gas-generators, the section being taken on the line 2 2 in Fig. 1. Fig. 3 is an enlarged cross-section of one of the tripping devices for the water-supply pipe. Fig. 4 is a plan view of part of the improvement. Fig. 5 is a plan view of one of the carbid-receptacles. Fig. 6 is an enlarged view illustrating the gas and water pipes and bells attached thereto, and Fig. 7 is an enlarged perspective view of two of the generators.

The improved acetylene-gas machine is provided with a number of receptacles proper, A A², each provided with a generator-casing formed by a bell B, fitting loosely into a pail B', the bell being secured to the lower end of a gas-delivery pipe C, discharging into a gas-pipe D, supported at one end on a standard E and extending with its other end into the tank F of a gasometer having the usual bell F'. The pipe D is provided with a branch pipe G, which opens into the bell F', and with a branch pipe G' for conveying the gas to the burners.

In each gas-delivery pipe C is arranged a three-way valve C' for connecting the interior of the generator-casing with the pipe D or 55 with a pipe H, leading to the outside of the building, so that when a generator is to be recharged with carbid the pipe D is cut off from the generator-casing and the latter is connected with the pipe H, so that no gas escapes 60 into the room. The stem of the valve C' is provided with a hand-lever C², which, when in a vertical position, establishes communication between the interior of the bell B and pipe D, and the pail B' is provided with a bail B², having a hooked end, by which it may be held on the pipe D to support the pail, as shown in Figs. 2 and 7. Now it will be seen that when the bail B² is hooked upon the pipe D then the pail B' is properly supported with the bell 65 B inside of the pail, as is plainly illustrated in Figs. 1, 2, and 7. When the apparatus is in operation, the valve C' is closed to the pipe H, and communication is established between the interior of the bell B and the pipe 70 D, and the hand-lever C² is in a vertical position against the pipe D. When it is desired to remove the pail B', it is necessary for the operator to swing the hand-lever C² downward 75 out of engagement with pipe D to permit of lifting bail B² off the pipe D for removing the pail B'; but at the same time such movement of the hand-lever C² causes a closing of the valve, so that no gas can escape through the pipe C to the pipe D, as the lower end of the 80 pipe C is connected with the pipe H.

The pail B' is adapted to contain a carbid-receptacle I, set on lugs B³ in the bottom of said pail and held in position against lateral movement therein by projections B⁴. In the 85 center of the receptacle I is arranged a pipe I', which opens at its lower end into the lower end of the pail B', so that water from the latter can rise in the pipe I' and pass through perforations I² into compartments I³, formed 90 in the receptacle, each compartment being charged with calcium carbid, the openings I² being located slightly above one another, so that the water passes successively to the several compartments. Thus the water passing 95 through the lowermost aperture I² first passes into one compartment and into the carbid contained therein to generate a new amount of gas, and when this carbid has been used 100

up and the compartment is filled with water the subsequent supply of water rises to the next higher opening I^2 and passes into the second compartment to repeat the above operation.

In order to keep the bell B cool on top, I extend the side wall of the bell to form a top receptacle B^5 , adapted to contain water for keeping the top of the bell cool.

- 10 Water is passed into each generator-casing through a branch pipe J , and the several branch pipes are connected with a water-supply pipe J' , containing a valve J^2 and opening into the bottom of a water-tank K , held on the upper end of the gasometer-tank F . A pipe L , connected with a source of water-supply, discharges into the tank K , and the latter is connected by an opening K' with the interior of the tank F to supply the said tank
- 15 F with water, said tank being also provided with an overflow-pipe K^2 for carrying off the surplus water. The pipe L is provided with a valve L' , having a float extending into the tank K , so that the level of the water is always maintained in said tank K . The stem J^3 of the valve J^2 is connected by a rod J^4 with the gasometer-bell F' , so that when the latter rises it finally closes the valve J^2 to shut off the water from the supply-pipe J' ,
- 20 and consequently from the branch pipes J . Each of the branch pipes J is provided with a valve J^5 , the valve-stem of which is provided with an arm J^6 , pivotally connected with the stem N' of a float N , mounted to rise and fall in a receptacle B^6 , formed in the top of the bell B , an opening B^7 leading into the space between the bell and the pail B' . It is evident that when the calcium carbid in the first generator A has been used up in its
- 25 several compartments water still passes through the branch pipes J into the generator-casing, to finally pass through the opening B^7 into the receptacle B^6 and lift the float therein, so that the stem N' in acting on the arm J^6 closes the valve J^5 , so that the water is shut off from this generator-casing. The arms J^6 of the valves, except the last one, are adapted to be engaged by a trip O , held on an arm O^2 , projecting from a shaft O' , journaled in suitable bearings carried by the water-supply pipe J' . When the float N of one of said generators rises to close the valve J^5 , as above described, then the arm J^6 passes under the trip O , (see Fig. 3,) whereby the
- 30 stem is automatically locked in place, and with it the float N . Thus the valve J^5 is locked, and the operator can now remove the pail of this generator to clean it and refill the receptacle I with fresh carbid.
- 35 When the water is shut off in the branch pipe J of the first generator A , the water flows through the pipe J to the second branch pipe for the generator A' , and the above-described operation is then repeated—that is, gas is now generated in the second generator—and when the carbid therein has been used up the water rises and acts on the float N of this gen-

erator so that the valve J^5 in the branch pipe J for the generator A' is closed, and water now flows through the pipe J' to the last generator A^2 . When generation of gas takes place in the generator A^2 , the other generator A' can be opened, cleaned, and supplied with fresh carbid and then replaced in position the same as the first generator A . When the calcium carbid in the last generator A^2 has been used up and the water rises in the receptacle B^6 and lifts the float N for this generator, then the valve J^5 in the branch pipe J for the generator A^2 is closed, and at the same time the arms J^6 of the valves J^5 of the preceding generators A A' are released by a connection of the float-stem N' of the generator A^2 with an arm O^3 on the end of the shaft O' . (See Figs. 1 and 2.) When the arms J^6 are released from the trips O , the weights of the floats N cause the arms J^6 to swing downward and open the valves J^5 for the generators A A' , so that the water can now again flow first to the first generator for the purpose above mentioned. Should a generator not be cleaned, as above described, the release of the trip O from the arm J^6 will not open the corresponding valve J^5 , as the float N for the uncleared generator will be held up by the water in the corresponding receptacle B^6 .

It is understood that the gas generated in a generator A , A' , or A^2 passes through the pipe C into the pipe D and from the latter into the gasometer and to the pipe G' for supplying the burners, the gas passing into the generator-bell F' raising the latter to the desired height; but in case of excess generation of gas the bell F' is lifted to such an extent that the valve J^2 is closed and the general supply of water to the branch pipes J is entirely shut off until the amount of gas in the gasometer has decreased and the bell F' has moved downward sufficiently to again open the valve J^2 . By the arrangement described the pressure of the gas in the gasometer does not exceed a predetermined amount.

By having a constant water seal in each of the generators A A' A^2 no gas is liable to escape into a room, and in case a generator is opened to be refilled with a fresh charge of calcium carbid the interior of the generator-bell B is connected by the valve C' with the waste-pipe H , leading to the outside, so that even then no gas is liable to escape into the room. It will further be seen that the water seal in the generator is changed every time the generator is recharged with calcium carbid, so that there is no possibility of the generator-casing becoming clogged by lime or other matter.

In first starting the machine it is necessary to fill the first generator-casing A with a sufficient quantity of water to rise in the pipe I' to the first compartment for generating the gas, which drives out the air from the generator-casing at the time the valve C' is still open to the pipe H , so that air and gas pass to the outside of the room, and when this air is

driven out the operator swings the hand-lever C² upward to close the valve C' to the pipe H and to connect the generator-casing with the pipe D at the same time the hand-lever C² 5 engages the bail B² to lock the latter in position on the pipe D.

Having thus fully described my invention, I claim as new and desire to secure by Letters Patent—

10 1. An acetylene-gas apparatus, comprising a water-supply pipe, a series of generators each having a branch-pipe connection with the said water-supply pipe, a valve in said branch-pipe connection, a float on each generator for closing and opening the said valve, a locking device arranged for engagement with the float when the latter is in raised position, substantially as shown and described. 15

20 2. An acetylene-gas apparatus, comprising a water-supply pipe, a series of generators each having a branch-pipe connection with the said water-supply pipe, a valve in said branch-pipe connection, and a float on each generator for controlling the said valve, the 25 float being mounted in a separate receptacle in the upper part of the generator, said receptacle having a connection with the generator-casing, so that when the water rises in said upper part of the generator it also passes 30 into the float and lifts the latter to close said valve, substantially as shown and described.

35 3. An acetylene-gas apparatus, comprising a water-supply pipe, a series of generators each having a branch-pipe connection with said water-supply pipe, a valve in said branch-pipe connection, a float on each generator for controlling the said valve, the float being mounted in a separate receptacle in the upper part of the generator, said receptacle having a connection with the generator-casing, so that when the water rises in said upper part of the generator it also passes into the float and lifts the latter to close said valve, and a locking device for the stem of the said 45 40 valve to lock it in place when lifted by the float, substantially as shown and described.

45 4. An acetylene-gas apparatus, comprising a water-supply pipe, a series of generators each having a branch-pipe connection with said water-supply pipe, a valve in said branch-pipe connection, a float on each generator for controlling the said valve, the float being mounted in a separate receptacle in the upper part of the generator, said receptacle having a connection with the generator-casing, so that when the water rises in said upper part of the generator it also passes into the float and lifts the latter to close said valve, and a locking device for the stem of the said 55 60 valve to lock it in place when lifted by the float, said locking device being controlled by

the float of the last generator in the series; substantially as shown and described.

5. An acetylene-gas generator, provided with a generator-casing comprising a fixed 65 generator-bell, a pail for containing said bell, a gas-pipe for supporting the bell and adapted to receive the bail of said pail to also support the latter, a carbide-receptacle in said pail, a water-receptacle on the top of said bell 70 and adapted to contain water to keep the top of the bell cool, and a float-receptacle in said water-receptacle, and having an opening leading to the space between the bell and the pail, substantially as shown and described. 75

6. In an acetylene-gas apparatus, a water-supply pipe provided with a valve, a generator to which said pipe is arranged to supply water, a float in said generator and connected with the stem of the valve to open and close 80 the latter, and a locking device arranged to hold said valve closed, as set forth.

7. In an acetylene-gas apparatus, a water-supply pipe, a valve in said pipe and having an arm on its stem, a generator to which said 85 pipe is adapted to supply water, a float in said generator and connected with the said arm whereby to open and close the valve, and a locking device arranged to engage said arm to hold the valve in closed position as set forth. 90

8. In an acetylene-gas apparatus, a supply-pipe, a series of generators each having a branch-pipe connection with said supply-pipe, a valve in each branch pipe, the stem of each valve being provided with an arm, a float in 95 each generator, said floats being connected with said arms to open and close the valves, a shaft mounted above the generators, trips secured to said shaft above the arm of each valve except the last and adapted to hold their respective valves closed, and a connection between the shaft and the valve of the last generator whereby the shaft will be turned to release the trips when the said float is raised, as set forth. 100 105

9. In an acetylene-gas apparatus, a supply-pipe, a series of generators arranged to receive water from said supply-pipe, valves adapted to control the supply, floats in the generators for opening and closing the valves, 110 a locking device at each generator except the last for automatically holding the respective valves in closed position, and a connection between the locking devices and the float of the last generator whereby the locking devices will release the valves when the said float is raised, as set forth. 115
